UNITED STATES PATENT OFFICE.

DAVID H. NATION, OF ST. LOUIS, MISSOURI, ASSIGNOR TO GILES F. FILLEY,
OF SAME PLACE.

RANGE.

SPECIFICATION forming part of Letters Patent No. 228,270, dated June 1, 1880.

Application filed April 6, 1880. (No model.)

To all whom it may concern:

Be it known that I, DAVID H. NATION, of St. Louis, Missouri, have made a new and useful Improvement in Ranges, of which the following is a full, clear, and exact description, reference being had to the annexed drawings, making part of this specification, in which—

Figure 1 is a top view of the improved range, a portion of the top plate being broken away; Fig. 2, a bottom view, the bottom plate being removed; and Figs. 3, 4, details, being vertical sections taken, respectively, on the line $x-x$ and the line $y-y$ of Fig. 1.

The same letters denote the same parts.

15 The present construction is an additional modification of one I have previously made, in which the features and advantages of a range and a three-flue cook-stove are combined.

The special advantage of this form of the range 20 is that the top of the range is thoroughly utilized, there being no blank or unoccupied spaces in the top plate between the opening. But a single division-strip is used in forming the flues at the top of the range, and but a single 25 damper is needed. The box-flue used in the former construction is done away with. The oven is not cut into, and the construction generally is simpler.

Referring to the drawings, A represents the 30 improved range, having the fire-place B, the flue C, leading from the fire-place, the diving-flues D D, the side bottom flues, E E, the center bottom flue, F, the ascending flue G, the flue-space H, the escape-flue I, and the oven J. 35 A strip, K, extends from the back side, a , of the range to the front side, a' . It is arranged on the farther (measured from the fire-place) side of the diving-flues, and the parts are so

proportioned as to bring the strip just between two sets of the openings in the top plate, a^2 , of 40 the range—say between the set L³ L³ and the set L⁴ L⁴. This enables all the openings L' L' L² L² L³ L³ L⁴ L⁴ to be brought compactly together, as shown, and thereby the capacity of the range is increased.

45 M M' represent a two-wing damper, by means of which the direct communication between the flues C and H can be closed—that is, there are openings d d just beneath the strip K, through which the heat-currents can pass 50 from the flue C across the upper ends of the flues D D into the flue-space H, and this is the course the heat-currents are allowed to take when it is not desired to heat the oven, but only the upper part of the range, and as 55 indicated in Fig. 1. But to heat the oven the damper is turned up, as shown in Figs. 3, 4, and the heat-currents then pass from the flue C down the diving-flues D D, and through the flues E, E, F, and G, into the space H, and 60 thence into the escape-flue I, as shown in Fig. 4.

I claim—

1. The combination, in the range A, of the flues C, D, D, H, and I, said flues C and H being separated by the strip K, extended and 65 arranged substantially as shown and described.

2. The combination in the range A, of the flues C D D E E F G H I and the damper M M', said flues C and H being separated by the strip K, extended and arranged substantially as shown and described. 70

DAVID H. NATION.
